UNITED STATES PATENT OFFICE

129,822

DESIGN FOR A HEARING AID APPARATUS CASE

William D. Penn, Dallas, Tex.

Application May 20, 1941, Serial No. 101,034

Term of patent 3½ years

To all whom it may concern:

Be it known that I, William D. Penn, a citizen of the United States, residing at Dallas, in the county of Dallas and State of Texas, have invented a new, original, and ornamental Design for Hearing Aid Apparatus Cases, of which the following is a specification, reference being had to the accompanying drawing, forming a part thereof, in which

Fig. 1 is a front elevational view of a hearing aid apparatus case showing my new design; Fig. 2 is a side elevational view; Fig. 3 is a top view and Fig. 4 is a bottom view.

The rear of the device is substantially plain.

I claim:

The ornamental design for a hearing aid apparatus case, as shown and described.

WILLIAM D. PENN.
